AIR CONDITIONING UNIT

Emert J. Lattner, Cedar Rapids, Iowa

Application September 10, 1937, Serial No. 163,237

4 Claims. (Cl. 261—106)

This invention relates to air conditioning apparatus and has particular relation to a means for heating, washing, circulating, humidifying and tempering air.

5 It is a general object of the invention to provide a compact and efficient air conditioning apparatus.

10 It is another object of my invention to provide new and improved washing and filtering apparatus for air conditioning, an improved arrangement of filtering members and improved means for mounting the washing and filtering members.

15 Other and further features and objects of the invention will be more apparent to those skilled in the art upon a consideration of the accompanying drawings and following specification, wherein is disclosed a single exemplary embodiment of the invention, with the understanding, 20 however, that such changes may be made therein as fall within the scope of the appended claims, without departing from the spirit of the invention.

In said drawings:

25 Figure 1 is a view, partly in section and partly in elevation, of a device constructed according to one embodiment of my invention.

Figure 2 is a view, partly in section and partly 30 in end elevation, of a device shown in Figure 1.

Figure 3 is a view in perspective of the cabinet of a device constructed according to one embodiment of my invention.

35 Figure 4 is a view in perspective of the device shown in Figure 1 but with portions of the casing removed to show the interior of the device.

Figure 5 is a fragmentary view in perspective of a by-pass valve for permitting direct communication between the primary combustion space and the stack, and,

40 Figure 6 is a fragmentary view in perspective of the motor support for the blower motor.

Referring now more particularly to Figure 1, a device constructed according to a preferred embodiment of my invention is preferably di-

45 vided into three compartments, such as the burner and control compartment 10, the warm air compartment 11, and the cold air compartment 12. These compartments are formed by means

50 of a rectangular cabinet 13 including floor plates 14, side walls 16 and 17, the top cover 18, and doors 19 and 21, front and rear respectively, the doors being made removable to permit ready access to the interior of the cabinet. The interior of the cabinet is divided off by a partition

55 22 between the burner compartment 10 and the

warm air compartment 11, and a second partition 23 between the warm air compartment 11 and the cold air compartment 12.

In the present instance, the oil burner 24 is preferably used for furnishing heat and the blast tube or manifold 26 projects into a combustion chamber 27 with the burner fastened on the outside of a door or closure 28 on the front of the combustion chamber. The closure or door 28 is adapted to be bolted to the casing 22 by means of 5 bolts 29, and to the furnace wall or plate 30. The combustion chamber lining, indicated at 31, is roughly in the form of a drawer, and the inner wall at the burner side of the chamber, as indicated at 32, is formed in a frusto-conical or 10 funnel form, with the manifold 26 at the apex of the funnel. The wall opposite to the burner is a vertical wall, as indicated at 33. Heat insulating material 34 is located between the combustion chamber lining 31 and the plate 28. It is to be 15 noted that, after removing the bolts 29, the entire combustion chamber may be removed by sliding it out like a drawer, with the oil burner still remaining in place if desired. This feature is of material advantage as it permits ready adjustment and cleaning of the oil burner and combustion chamber.

The member 37 is a hot water coil of usual construction and this is supported by means of a plate 38 on the front of the partition 22, and 30 the coil projects into the primary combustion space 39 just above the combustion chamber 31. The lower portion of the primary combustion space or chamber 39 is preferably lined with fire-brick as indicated at 41. The furnace casing is 35 indicated at 42 and this is a cylindrical member having a top closure 43 and a bottom closure 44. The casing is adapted to rest on the base 46, and the base has openings 47 therein to permit warm air to enter the base of the furnace casing.

I preferably provide a cylinder 51 leading through the wall 42 of the furnace into the primary combustion space 39. The outer end of this cylinder is secured to the partition 22 by means of ring 52 and cover ring 53, the outer 45 edge of the cover ring 53 being inclined as indicated at 54, and being provided with a cover 56 held in place by means of a hinge 57. The slope of the ring 53 at 54 is such that the weight of the cover keeps it closed, but if there is an excess of pressure within chamber 39, the cover will be blown open to relieve the pressure.

The heated products of combustion pass upwardly, as indicated by the arrows, through the primary combustion chamber 39 and when they 55

reach the top of this chamber, they pass into a plurality of radially disposed flues 58. These flues are spaced from the outer wall 42, as indicated at 59, and thus afford passageways from all 5 sides of the flues and of the outer wall 42 over which cold air may readily pass and be heated. The heated gases pass downwardly through the flues 58 and enter the chamber 61 at the bottom of the furnace, which chamber may be termed 10 the expansion chamber. Clean-outs are provided at 62 at the lower ends of the flues 58.

The hot gases then pass upwardly through a channel at 63 as indicated by the arrows. This channel is formed by the partition 64 which is 15 located behind the combustion chamber 31. If desired, direct communication between the primary combustion space 39 and the channel or conduit 63 is afforded by means of a by-pass 66, and this by-pass is constructed of a base 65 and 20 a rotatable cap 70 having a co-operating opening 75 (see Figure 1) so that it may be opened, closed or partly closed, however it is adjusted. This by-pass serves several purposes, among 25 which are that it can be adjusted so as to secure maximum efficiency from the furnace by regulating the temperature of the flue gases and it also serves the purpose of eliminating puffs and pulsations occurring in the front of the furnace. The gases in the conduit 63 have lost most 30 of their heat by the time they enter this conduit, but are still at a temperature of some four hundred or five hundred degrees. The gases pass on out through the flue 67, as indicated by the arrows and on up through the chimney (not 35 shown). It is to be noted that the flue 67 passes through the cold air chamber 12 and thus affords means for warming the cold air as it passes through this chamber.

The cold air compartment preferably has at 40 least two mechanisms located within it, one being the blower unit 68 of conventional construction supported by the bracket 69 on base 14, and having the discharge conduit 71 projecting through the wall 23 into the chamber 72 surrounding the furnace. The rotor of the blower 45 is driven by means of a pulley 73 and belt 74 from the motor 76. The motor 76 is mounted on an arm or platform 77 which is pivotally engaged to a rod 78. The arm 77 may both pivot 50 on this rod 78 and slide on the arm parallel with the blower shaft. This structure is better shown in Figure 6. It is apparent that the motor 55 may be adjusted in a direction parallel to the blower shaft until the belt 74 is in proper alignment, and furthermore that the weight of the motor 76 acting on the pivot and rod 78 will keep the belt 74 taut. This structure is of material 60 advantage as it permits ready adjustment to suit all of the motor sizes used for driving blowers of this character and furthermore permits the use of different sized pulleys without changing the belt.

The upper portion of the cold air chamber is 65 preferably provided with wet filters 81 and dry filters 82. The pair of filters 81 and 82 are placed in opposed inclined position with the upper edges of the filter 81 spaced apart sufficiently 70 that their upper edges define an area approximately that of the cold air intake conduit 83. The partitions 84 close off the top of the filter chamber from the tops of the screens 81 to the wall, thus forcing the air passing downward through the inlet 83 to pass through the wet screens 81. The wet screens 81 rest in a tray 75 86 and any excess moisture from the screens may

be drained off through the drain 87. Moisture is supplied to the screens through the agency of the conduit 88 controlled by valve 89, the conduit 91, and the spray nozzle 92. Of course, any other method of supplying water may be employed, 5 as for instance conduits leading directly to the screens.

The dry screens 82 are arranged within the filter chamber in slightly more inclined position than the wet screens 81. The upper edges of the 10 dry filters 82 rest against the walls of the cabinet, the lower edges being placed adjacent the edges of the pan 86. The air is thus forced to pass through these dry screens as well as the 15 wet screens 81. The wet screens constitute means of washing, and filtering the air and imparting moisture to it, while the dry screens constitute means for filtering the air after it has been washed by the wet screens. This structure has advantages of easy control of the humidity 20 and it is easy to secure proper humidity by controlling the amount of water deposited on the wet screens 81 by means of the nozzle 92, the flow of water through the nozzle being controlled by the valve 89 in accordance with the humidity 25 requirements. The large direct particles are removed by the washer filters 81, thus prolonging the life of the dry filters 82. These dirt particles tend to be flushed into the pan 86 and to be discharged through the drain 87. 30

The operation of the air-conditioning unit is as follows: The oil burner 24 furnishes combustible fuel to the combustion chamber 27 where the fuel is burned. The gases from the burning fuel pass upwardly through a secondary combustion chamber, heating the walls thereof. The gases then pass downwardly through the flues 58 on the outside of the furnace casing and into an expansion chamber in the bottom of the furnace casing. They are then passed up the back 40 of the furnace casing and through the flue or stack 67, to heat the cold air coming into the unit. The cold air coming into the unit enters at the intake 83 and passes through the wet filters 81, the dry filters 82, into the blower 68 and 45 is driven forcibly into the furnace chamber 11. The air from the blower passes around the furnace casing 42 and around the flues 58 and then upwardly through the exhaust or hot air shaft 94 into the space to be heated. In passing through 50 the filters 81 the air is properly humidified and a portion of the dirt removed. The air then passes through the filters 82 where dust particles are removed and is then driven forcibly through the system by means of the blower. 55

Although I have described a specific embodiment of my invention, it is apparent that modifications may be made by those skilled in the art. Such modifications may be made without departing from the spirit and scope of my invention as set forth in the appended claims. 60

I claim as my invention:

1. In an air conditioning device, a filter chamber open top and bottom, a pair of filter screens in the filter chamber in sloping V position with relation to each other with the top edges spaced apart to span the opening in the top of the filter chamber and the bottom edges close together, a drain pan for supporting the filter screens at the bottom edges spanning the bottom edges to close off the space at the bottom of the screens and catch any excess water dripping from the screens, a spray nozzle disposed between the screens and within the top opening in the filter chamber positioned to spray water on the inner walls of the 70 75 70 75 75

- screen to moisten the air passing through the screens, and two more filter screens also in sloping relation with respect to each other positioned on opposite sides of the first pair of filter screens
- 5 5
5 with the bottom edges supported by the drain pan and the upper edges resting against the opposite side walls of the filter chamber.
2. In an air conditioning device, a filter chamber open at top and bottom, a pair of filter screens in the filter chamber in V position with relation to each other with the top edges spaced apart to span the opening in the top of the filter chamber and the bottom edges close together so that they may be supported and closed by a common support, means between the screens for depositing water thereon, a drain pan below the screens for catching the excess water, the lower edges of the screens being supported on the drain pan, whereby air entering the filter chamber through the top
- 10 10
10 must flow through the filter screens and is split apart into two air streams to centralize the air stream and permit the largest available size screen to be used in the chamber, and means for removing water deposited in said pan.
- 25 3. In an air conditioning device, a filter chamber open top and bottom, a pair of filter screens in the filter chamber in sloping V position with relation to each other with the top edges spaced apart and the bottom edges close together, a drain pan below the screens and spanning the bottom edges of the screens to close off the space at the bottom of the screens and catch any excess water drip-

ping from the screens, the lower edges of the screens being supported by the pan, means for supplying water disposed between the screens within the top opening in the filter chamber and positioned to direct water on the inner faces of the screens to moisten the air passing through the screens, means for removing water deposited in said pan, and baffle plates within the chamber to prevent the passage of air except through the filters.

4. In combination with a warm air furnace having a return air chamber, a return air opening near the top of the chamber, a plurality of wet filters within the chamber having their top edges spaced apart to furnish an open area at least 15 equal to the area of the return air opening, the lower edges of the wet filters being located adjacent each other and within a drain pan, baffle means within the chamber to cause all air passing through the chamber to pass first through the 20 wet filters, other filters of a dry type positioned within the chamber and after the wet type filters, other means for baffling the chamber to force all air passing through the wet filters to also pass through the dry filters, a spray nozzle located between the wet filters for flooding the wet filters with water, and means for controlling the spray of water to the spray nozzle in accordance with the amount of humidity required in the air being treated.

EMERT J. LATTNER.
